(57) **CLAIM**

The ornamental design for a glow in the dark spoon fishing lure with a slot that receives a glow in the dark cartridge, as shown and described.

DESCRIPTION

FIG. 1 is a top perspective view of the glow in the dark spoon fishing lure with a slot that receives a glow in the dark cartridge;

FIG. 2 is a bottom perspective view thereof;

FIG. 3 is a top plan view thereof;

FIG. 4 is a bottom plan view thereof;

FIG. 5 is a side elevation view thereof;

FIG. 6 is an opposite side elevation view thereof;

FIG. 7 is a front elevation view thereof;

FIG. 8 is a rear elevation view thereof;

FIG. 9 is a cross sectional view shown along line 9-9 of FIG. 4;

FIG. 10 is a cross sectional view shown along line 10-10 of FIG. 6;

FIG. 11 is a top perspective view of the glow in the dark spoon fishing lure with a slot that receives a glow in the dark cartridge, showing the cartridge positioned within the slot of the main body;

FIG. 12 is a bottom perspective view thereof;

FIG. 13 is a top plan view thereof;

FIG. 14 is a bottom plan view thereof;

FIG. 15 is a side elevation view thereof;

FIG. 16 is an opposite side elevation view thereof;

FIG. 17 is a front elevation view thereof;

FIG. 18 is a rear elevation view thereof; and,

FIG. 19 is a cross sectional view shown along line 19-19 of FIG. 16.

The broken lines shown represent the environment and represent unclaimed subject matter and form no part of the claimed design.

1 Claim, 15 Drawing Sheets
